INVENTOR
Andrew A. Kramer.
BY Arthur G. Brown.
ATTORNEY.

UNITED STATES PATENT OFFICE.

ANDREW A. KRAMER, OF KANSAS CITY, MISSOURI.

VEHICLE-TANK STRUCTURE.

1,394,742.

Specification of Letters Patent. Patented Oct. 25, 1921.

Application filed April 14, 1920. Serial No. 373,977.

To all whom it may concern:

Be it known that I, ANDREW A. KRAMER, a citizen of the United States, residing at Kansas City, in the county of Jackson and State of Missouri, have invented certain new and useful Improvements in Vehicle-Tank Structures; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to a vehicle tank structure, the primary object being to provide a strong, durable tank which will not break down under the shocks and vibrations to which the tank is subjected during its normal travel over road beds.

It is also the purpose of my invention to generally improve tank structures of this general class and to this end the invention consists in certain novel parts and arrangements of parts which will be referred to hereinafter, reference being had to the accompanying drawings, in which—

Figure I is a perspective view in section of a tank constructed in accordance with my invention.

Fig. II is a detail perspective view of one of the cross-tie members, and

Fig. III is an end view of a slightly modified form of tank construction.

Referring now to the drawings by numerals of reference:

1 and 2 designate the longitudinal side sills of a substantially rectangular frame, the side sills having inwardly bent lower flanges 3 and 4 respectively. The upper portions of the side sills are shown as extending a considerable distance into the tank proper, as indicated at 5 and 6, and have openings 7 and 8 respectively to provide surge sheets longitudinally of the tank. The tank proper is shown as supported by the longitudinal side sills of the frame and in the construction shown in Fig. I, the tank is formed by bending a sheet or sheets 9 in substantially cylindrical form, the ends of which are provided with depending projections 10 and 11, which are secured to the outer faces of the longitudinal side sills 1 and 2. The space between the side sills is bridged by a floor plate 12, having depending flanges 13 and

14, which are also fastened to the side sills but secured to the inner faces thereof so that the tank is formed as a substantially integral structure consisting of the longitudinal side sills, the surge plates, the floor plate and the curved body portion. It is understood that the flanges 10 and 11, as well as the flanges 13 and 14 may be autogenously soldered or welded to the side sills 1 and 2.

Beneath the tank body proper I prefer to arrange cross tie members consisting of plates 15, having end flanges 16 and 17 adapted to be fastened to the webs of the longitudinal side sills 1 and 2 by bolts or other fastening devices 18 and 19. The intermediate portions of the tie members are provided with pipe openings 20 to receive and support the longitudinal pipes 21, which lead from the several compartments of the tank. The fastening devices 18 and 19 may also be utilized for securing the can rack brackets or supports 22 and 23 to the longitudinal side sills, as clearly shown in Fig. I. The brackets may consist of web portions 80 provided with lateral flanges 24 and vertical flanges 25, the vertical flanges receiving the fastening devices 18 and 19 and the lateral flanges supporting the can rack.

In Fig. III I have shown a slightly modified form of support in which the longitudinal side sills 26 and 27 are of substantially Z-beam form with the tank resting upon the outwardly flared flanges 28 and 29, to which it may be autogenously soldered or welded. 90 The construction of tank in Fig. III will conform to the usual construction, it being obvious that the tank may be set upon the flanges 28 and 29 and welded thereto so that a substantially integral construction 95 will be provided.

What I claim and desire to secure by Letters-Patent is:

1. In a vehicle tank structure, longitudinal sill members, a body sheet having depending, longitudinal edge flanges attached to the outer walls of the sill members, and a bottom sheet having depending, longitudinal edge flanges attached to the inner walls of the sill members and coöperating with the body sheet and sill members to form a tank body.

2. In a vehicle tank structure, longitudinal sill members, a body sheet having depending, longitudinal edge flanges attached to the outer walls of the sill members, a bottom sheet having depending,

longitudinal edge flanges attached to the inner walls of the sill members and co-operating with the body sheet and sill members to form a tank body, and can 5 rack brackets attached to the outer walls of the sill members.

3. In a vehicle tank structure, longitudinal sill members, a body sheet having depending, longitudinal edge flanges attached 10 to the outer walls of the sill members, a bottom sheet having depending, longitudinal edge flanges attached to the inner walls of the sill members and co-operating with the body sheet and sill members to form a tank 15 body and cross tie members secured to the inner walls of the sill members and supporting the bottom plate.

4. In a vehicle tank structure, longitudi-

nal sill members, a body sheet having depending, longitudinal edge flanges attached 20 to the outer walls of the sill members, a bottom sheet having depending, longitudinal edge flanges attached to the inner walls of the sill members and co-operating with the body sheet and sill members to form a 25 tank body, the upper portions of the sill members projecting into the tank body and constituting surge plates.

5. A tank structure comprising side sills having upwardly extending integral surge 30 sheets, and a tank secured to the side sills below the surge sheets.

In testimony whereof I affix my signature.

ANDREW A. KRAMER.
